UNITED STATES PATENT OFFICE.

PRITCHARD STEWART, OF CHICAGO, ILLINOIS, ASSIGNOR TO HIBBARD, SPENCER, BARTLETT & COMPANY, OF CHICAGO, ILLINOIS, A CORPORATION OF ILLINOIS.

DESIGN FOR A SPOON, FORK, OR SIMILAR ARTICLE.

51,245.

Specification for Design.

Patented Sept. 4, 1917.

Application filed March 29, 1917. Serial No. 158,479. Term of patent 7 years.

To all whom it may concern:

Be it known that I, PRITCHARD STEWART, a citizen of the United States, residing at Chicago, in the county of Cook and State of Illinois, have invented a new, original, and ornamental Design for Spoons, Forks, or Similar Articles, which is illustrated in the accompanying drawing, forming a part of this specification.

Figure 1 of the drawing is a front elevation, or view of the obverse side of a spoon embodying my present design, and

Fig. 2 is a fragmentary, rear view of the spoon handle.

What I claim is:

The ornamental design for a spoon, fork or similar article, as shown.

PRITCHARD STEWART.
